UNITED STATES PATENT OFFICE.

CLARENCE D. PLATT, OF BRIDGEPORT, CONNECTICUT.

ELECTRIC SWITCH.

1,337,469.

Specification of Letters Patent.

Patented Apr. 20, 1920.

Application filed May 1, 1919. Serial No. 294,044.

To all whom it may concern:

Be it known that I, CLARENCE D. PLATT, a citizen of the United States of America, residing at Bridgeport, Connecticut, have 5 invented a new and useful Electric Switch, of which the following is a specification.

My present invention relates particularly to the contact mechanism of electric switches, the objects of the invention being 10 primarily to provide switch contacts of simple construction which will have a high current carrying capacity.

Other objects of the invention are to insure good electrical contact and to eliminate 15 arcing or burning of the contact faces.

Briefly stated, the invention consists of a special substantially C-shaped contact mounted for movement toward and away from the relatively stationary contacts, said 20 contact being constructed of a strip of spring metal and adapted to have the in-turned freely yielding ends thereof forced into flat engagement with the stationary contacts. The ends of this C-shaped contact are preferably formed with outwardly 25 directed lugs, which in the circuit breaking operation constitute terminals to take care of any arc which may form or tend to form.

For the sake of a more complete disclosure of the invention attention is invited to the accompanying drawing wherein I have shown the invention embodied in a practical and commercial form. It will be understood however, that the structure may be 35 modified in certain respects without departure from the true spirit and scope of the invention.

Figure 1 of said drawing is a plan view of an inclosed switch, the cover being open 40 and shown as broken away.

Fig. 2, is a broken sectional view taken substantially on the plane of the line 2—2 of Fig. 1. In this view the parts are indicated as in the circuit-closing movement.

45 Fig. 3, is a sectional view similar to Fig. 2 showing the switch parts in the entirely "closed" position.

Fig. 4, is a view of the same parts showing the switch at the moment of "break" 50 in the circuit-opening operation.

Fig. 5, is a detail perspective view of one of the movable spring contacts.

The switch illustrated is of the double pole type embodying two pairs of spaced contacts 7 and 8 shown simply as flat strips

or plates secured on the face of a flat base 9 and movable contacts 10 and 11 for bridging said spaced contacts.

These bridging contacts consist each of a strip of spring metal having a normally outwardly bowed back portion 12 and inturned end portions 13 connected with the ends of the back portion by the reverse bends 14, the whole forming a substantially C-shaped structure, as indicated. 60

The two contact springs are carried by a support in the form of a movable cross bar 15 slidably guided on the pins 17 upstanding from the base. The contact springs are secured to the supporting bar by screws 16 65 and it will be noted with this construction that the back portions of the springs are engaged by the support only at the points where they are secured thereto and that the ends of the back portions extending to opposite sides of the supporting bar are free 70 of said support and can yield in both directions.

A spring 18 is shown engaging with the cross bar for shifting the movable switch 80 element in circuit-opening direction and mechanism for shifting this element in the opposite direction is shown in the form of a lever 19 which engages with a bearing plate 20 on the top of the supporting bar 85 15 and which lever is actuated by a lug 21 on the operating shaft 22, said lug engaging with spaced stops 23, 24 on the lever 19. The shaft 22 is provided with a suitable handle 25 disposed at the outside of the box 90 26 in which the switch is mounted.

In closing the switch, the handle 25 is rocked downwardly as indicated in Fig. 2 to carry the lug 21 into engagement with the stop 24, whereupon the lever 19 operates 95 as a cam against the bearing plate 20 to force the support toward the switch base. In this movement the tips of the C-shaped contact springs are first brought into engagement with the ends of the spaced flat 100 contacts and as the movement continues these bent-under ends flatten out as indicated in Fig. 3 into flat engagement with the stationary contacts, forming contact "pads" of relatively wide area and consequently great current carrying capacity. The parts are preferably so designed that the circuit-closing mechanism will have a movement sufficient to buckle the normally outwardly bowed back portion of the spring 105

contact in the reverse direction, as shown in Fig. 3, to thus apply added tension and insure firm positive engagement. This structure, I find, has a remarkably high current carrying capacity which I attribute in part to the relatively broad contact faces and to the firm flat engagement of these parts.

In the circuit-opening movement the handle is rocked in the reverse direction or upwardly as indicated in Fig. 4, the lug 21 in this case engaging the stop 23 and rocking the lever 19 out of holding engagement with the bearing plate. As the lever 19 swings downwardly, a point is reached where the spring 18 asserts itself and snaps the movable switch element quickly outward rupturing the circuit with a quick break. The parts are illustrated in Fig. 4 as approximately at the moment when the spring is acting to snap the movable switch element to the open-circuit position. To guard the movable contacts against injurious arcing at such time, I preferably provide the ends of the contact spring with angularly and outwardly extending lugs 27 which, in the closed position of the switch over-lie the ends of the stationary contacts as indicated in Fig. 3 and which, in the circuit-opening movement, provide the nearest points to the ends of the stationary contacts and hence form terminals for the arcs, in case there is a tendency for the production of an arc or arcs. These lugs thus provide points which can be burned more or less without injuring the normal current-carrying parts of the switch.

I claim:—

1. In a double break electric switch, the combination of spaced contacts having exposed contact faces disposed in substantially the same plane, a bridging contact comprising a strip of spring metal having reversely bent free end portions and means for forcing said bent under end portions into flat

engagement with the contact faces aforesaid.

2. In an electric switch, the combination with spaced contacts, of a bridging contact comprising a strip of spring metal having a back portion and reversely bent free end portions disposed beneath said back portion and adapted for engagement with the spaced contacts and means for moving the bridging contact bodily and forcing both ends into engagement with the spaced contacts, said means being constructed to buckle the back portion of said bridging contact to thereby increase the spring tension of said contact against the spaced contacts.

3. In a switch of the character described, the combination of spaced contacts, a substantially C-shaped bridging contact having inturned end portions for flat engagement with the spaced contacts and angularly bent tips at the ends of said inturned end portions and providing arcing terminals overlying the ends of the spaced contacts in the closed condition of the switch.

4. In a double break switch of the character described, spaced contacts, a bridging contact comprising a flexible strip having a normally outwardly bowed back portion and inturned free end portions doubled under said back portion and operating means for forcing both of said bent under end portions of the contact strip into engagement with the spaced contacts, said operating means having a movement in the circuit closing direction sufficient to buckle the normally outwardly bowed back of the contact in the opposite direction.

5. In a switch of the character described, the combination of spaced contacts and a bridging contact having reversely bent end portions engaging the faces of the spaced contacts and angularly bent tips extending over but spaced from the ends of the spaced contacts.

CLARENCE D. PLATT.
